UNITED STATES PATENT OFFICE

164,246

RECORDING APPARATUS

Harold W. Lindsay, Redwood City, Calif., assignor
to Ampex Electric Corporation, San Carlos,
Calif., a corporation of California

Application July 5, 1950, Serial No. 10,966

Term of patent 14 years

(Cl. D26—14)

To all whom it may concern:

Be it known that I, Harold W. Lindsay, a citizen of the United States of America, and a resident of the city of Redwood City, county of San Mateo, State of California, have invented a new, original, and ornamental Design for Recording Apparatus, of which the following is a specification, reference being had to the accompanying drawings, forming a part thereof.

Fig. 1 is a top plan view of a recording apparatus showing my new design;

Fig. 2 is a side elevation view looking from left to right on Fig. 1;

Fig. 3 is an end elevation view looking from bottom to top of Fig. 1; and

Fig. 4 is a side elevation view looking from right to left on Fig. 1.

The dominant features of my design reside in the portions shown in full line of the drawings.

I claim:

The ornamental design for a recording apparatus, substantially as shown and described.

HAROLD W. LINDSAY.
